Attorney

UNITED STATES PATENT OFFICE.

JOHN A. WELCH, OF FORT DODGE, IOWA.

HOG-WATERER.

1,333,519.

Specification of Letters Patent.

Patented Mar. 9, 1920.

Application filed July 14, 1919. Serial No. 310,838.

To all whom it may concern:

Be it known that I, JOHN A. WELCH, a citizen of the United States, residing at Fort Dodge, in the county of Webster and State of Iowa, have invented new and useful Improvements in Hog-Waterers, of which the following is a specification.

My invention relates to an animal waterer, and aims to more particularly provide a device of this nature adapted for use more particularly with hogs.

This invention presents improvements over the art of record, in that it includes a device of the nature specified, which will 15 keep fluid within it warm in winter and cool in summer, although exposed to the elements.

The structure shown in the drawings further aims to provide a waterer, the main reservoir of which, may be readily filled, together with a very simple construction, which will render the device very cheap to manufacture.

In the accompanying drawing, Figure 1 is a sectional side view of my device, and

Fig. 2 a plan view on the line 2—2 of Fig. 1.

In these drawings, the reference numeral 30 1 represents an outer-casing or jacket, upon which is mounted a head, or roof of any desired shape, such head or roof having at its apex a ventilator 2 of any approved construction. The lower edges 3 of the head 35 overlap the upper edges of the cylindrical casing.

A base portion 4, engages the lower edges of the casing, which base portion terminates in a pair of troughs 5 and 6, located at 40 diametrically opposite points, as shown in Fig. 2.

The outer edges of the troughs 5 and 6 overlap, as at 7, a cylindrical base member 8 which extends from such troughs to the 45 ground.

Secured to the inner face of such base member are legs 9, which terminate at their upper extremities in L's, supporting a tank 10, located within the casing 1, such tank 50 10 being of smaller diameter than the casing 1 and being located concentrically with respect thereto, so that an annular space is provided between the two, which space extends all the way around.

55 The upper end of the tank 10 is bowl-shaped, as at 11, an opening 12 being pro-

vided at the lowest portion of such bowl, to which is connected a pipe 13, extending downwardly and terminating at a point slightly above the lowermost portion of the 60 tank. A vent 14 is provided, so that water may be poured into the tank 10 by means of the bowl 11 and pipe 13 and permit the air to escape by means of such vent 14. A pair of L-shaped pipes 15 and 16 afford communication between the base of the tank and the two troughs 5 and 6 respectively. A pair of connecting pipes 17 and 18, connect the pipes 15 and 16 to one another at a point exteriorly of the tank 10. 70

It will be noted upon reference to Fig. 2 that each one of the pipes 17 and 18 forms a semi-circle, so that they both combined form a complete circle.

A pair of lamps 19 and 20 are provided, 75 as shown in Fig. 2, such lamps being positioned at a point directly below the pipes 17 and 18 and between the two troughs on each side of the center of the tank.

In operation it will be seen now that in 80 warm weather the lamps may be dispensed with and by virtue of the air space existing in the annular jacket surrounding the tank 10, the fluid in said tank will be kept comparatively cool, while in winter, with the 85 assistance of the lamps, or other suitable heating elements, the water in the troughs will be kept from freezing by virtue of the circulation of the fluid through the pipes 17 and 18 directly above the lamps and in the 90 tank proper by means of the products of combustion from said lamps passing into the annular space between the casing 1 and tank 10 at points in the circumference of the casing, not occupied by the troughs. 95 The heated air will then pass upwardly and finally pass into the outer atmosphere through the ventilator 2.

It will be seen that it is extremely simple to fill the tank 10, by simply removing the 100 head or roof 3 and pouring water as fast as desired into the bowl-shaped head 11 of the tank 10, after opening the vent plug 14. The head 11 will simply act as a funnel and allow the water or other fluid to pass down 105 through the pipe 13, until the desired quantity has been introduced into the tank 10.

Having now described my invention, what I desire to claim is:—

The herein described stock watering device comprising a casing open at the lower end and having a movable cover at the top,

and also having downwardly and inwardly extending base portions and troughs under and overhung by said base portions; a tank in said casing and of less diameter than the 5 casing so that the wall of the tank is spaced from that of the casing, a cylindrical base member in which said troughs are secured, legs extending upwardly from the base mem-

ber and supporting the tank, water pipes connecting the troughs with the tank, water 10 circulating pipes connecting the first named pipes, and heating means arranged directly under said water circulating pipes and within said base portion.

JOHN A. WELCH.
